US0D1062368S

(12) **United States Design Patent** (10) Patent No.: **US D1,062,368 S**
(45) Date of Patent: ** Feb. 18, 2025

(54) **TILTED AND RECESSED CONTROLLER PANEL FOR AN OUTDOOR GRILL**

(71) Applicant: **Traeger Pellet Grills, LLC**, Salt Lake City, UT (US)

(72) Inventors: **John Mabry**, Kalamazoo, MI (US); **Adam Gilleland**, Draper, UT (US); **Cristiana Behnken**, Salt Lake City, UT (US); **Louise McGowin**, Salt Lake City, UT (US); **Ethan Gibson**, Salt Lake City, UT (US)

(73) Assignee: **Traeger Pellet Grills, LLC**, Salt Lake City, UT (US)

(**) Term: **15 Years**

(21) Appl. No.: **29/865,842**

(22) Filed: **Aug. 16, 2022**

(51) LOC (15) Cl. **07-02**

(52) U.S. Cl.

USPC **D7/406; D7/334**

(58) **Field of Classification Search**

USPC D7/323, 337, 339, 340, 341, 362, 402, D7/406-409, 354, 360, 667, 334;

(57) **CLAIM**

The ornamental design for a tilted and recessed controller panel for an outdoor grill as shown and described.

DESCRIPTION

FIG. 1 is an upper right perspective view of our new design; FIG. 2 is an enlarged partial view of FIG. 1;

FIG. 3 is an upper left perspective view thereof;

FIG. 4 is front plan view thereof;

FIG. 5 is a lower left perspective view thereof; and,

FIG. 6 is a lower right perspective view thereof.

The even broken lines in FIGS. 1-6 illustrate unclaimed subject matter and do not form any part of the claimed design. The dashed-dot broken lines in FIGS. 1-6 illustrate the boundary of the claimed design.

1 Claim, 6 Drawing Sheets
